BOX OR CONTAINER

Charles F. McAleer, Kalamazoo, Mich., assignor
to Sutherland Paper Company, Kalamazoo,
Mich., a corporation of Michigan

Application July 11, 1938, Serial No. 218,600

2 Claims. (Cl. 229—36)

This invention relates to improvements in boxes or containers.

The main objects of this invention are to provide an improved box or container for packaging merchandise which is very strong and secure when set up even when made of comparatively light material, the parts being retained in assembled or set-up position without the aid of adhesives.

10 A further object is to provide a container or box having these advantages which may be made in a wide range of sizes such for example as suit boxes and it is also desirable for use in the packaging of food products.

15 Objects relating to details and economies of the invention will appear from the description to follow. The invention is defined and pointed out in the claims.

A preferred embodiment of the invention is 20 illustrated in the accompanying drawing, in which:

Fig. 1 is a perspective view of a box or container embodying my invention set up and with the cover closed.

25 Fig. 2 is an enlarged fragmentary longitudinal section on line 2—2 of Fig. 1.

Fig. 3 is an enlarged fragmentary transverse section on line 3—3 of Fig. 1.

Fig. 4 is a plan view of the blank from which 30 the box is formed.

Fig. 5 is a perspective view illustrating steps in setting up the box.

As illustrated in the accompanying embodiment of my invention, my improved box or container is preferably formed of an integral blank shown in the flat in Fig. 4. This comprises a bottom 1, side walls 2 and 3, and end walls 4. The side walls 3 are provided with inner end wall extensions 5 extending from the ends of the side walls and provided with interlocking notches 6 disposed so that when these inner side wall extensions are folded or swung to erected position, the notches may be engaged or interlocked thereby securing the side walls in their erected parallel position.

45 The outer end walls 4 are provided with tucking flap extensions 7 at their outer ends.

The side wall 3 is provided with a cover 8 extending from the outer edge of the side wall. The cover is provided with a side wall extension 9 at its outer end, the side wall extension being provided with end tucking flaps 10 at its ends.

50 The blank is preferably scored as indicated by the dotted lines 11 between the various parts enumerated to facilitate folding.

In setting up the box from a blank formed as shown in Fig. 1, the sides 2 and 3 are turned upwardly to a position at right-angles to the bottom, the inner end wall extensions 5 being swung to position and interlocked as the side walls are 5 brought to their final upright position. This provides a complete box. When it is desired to close the box, the cover is swung to closed position and the side wall flap 9 brought to lapping position along the fold of the box as shown in 10 Figs. 1 and 3 and the end wall tucking flaps 10 disposed against the outer sides of the inner end walls formed by the end wall flaps 5. The outer end walls are then swung to erected position, the tucking flap 7 being inserted between the cover 15 and the upper edges of the inner end walls formed by the extensions 5 and also between the cover and the upper edges of the extensions 10, and when the ends are pressed up to closed position, they are very securely retained by their 20 tucking flaps.

The completed box is attractive in appearance, is quite strong and rigid—that is, strong and rigid in proportion to the weight of material employed, and further, there are no gapping openings between the various parts.

My invention is well adapted for use in boxes or containers of varying sizes and for varying purposes. I have illustrated and described one practical embodiment. It will be understood that 30 I have used the terms side and ends as relative terms for convenience in description but that the box may be perfectly rectangular if so desired.

Having thus described my invention, what I 35 claim as new and desire to secure by Letters Patent is:

1. A box or container formed of an integral blank and comprising a bottom, side and outer end walls, the side and outer end walls extending from the edges of the bottom, the side walls being provided with inner end wall extensions foldable within the outer end walls and provided with interlocking notches, the outer end walls being provided with tucking flap extensions, and 40 a cover extending from the outer edge of one of the side walls, the cover being provided with a side wall cover extension, the cover side wall extension having end tucking flap extensions at its ends, the end wall tucking flaps being insertable between the upper edges of the inner end walls and the cover, and the cover end tucking flaps lying between the said outer end walls and the said inner end walls.

2. A box or container comprising a bottom, 45

side and outer end walls, the side and outer end walls extending from the edges of the bottom, the side walls being provided with interlocking inner end wall extensions, the outer end walls being provided with tucking flap extensions, and a cover extending from the outer edge of one of the side walls and having a side wall cover extension at its outer edge, the cover side wall ex-

5 tension having end tucking flap extensions at its ends, the end wall tucking flaps being insertable between the upper edges of the inner end walls and the cover, and the cover end tucking flaps lying between the said outer end walls and the said inner end walls.

CHARLES F. MCALLEER.
